D Company, Detroit, Mich., a corporation of
Michigan

Application February 27, 1942, Serial No. 432,562

6 Claims. (Cl. 200—116)

This invention relates to devices for making and breaking electric circuits and more particularly to automatic circuit breakers.

The object of the present invention is to provide an automatic electric circuit breaker having improved means for indicating an automatic trip condition.

Other objects and features of the invention will be readily apparent to those skilled in the art from the following specification and the appended drawing illustrating certain preferred embodiments of the invention in which:

Figure 1 is a front elevational view of an enclosed circuit breaker according to the present invention.

Figure 2 is an enlarged sectional view taken on the line II—II of Figure 1.

Figure 3 is a view similar to Figure 2 but with the operating parts shown in automatic tripped position.

Figure 4 is a sectional view taken on the line IV—IV of Figure 2.

The circuit breaker according to the present invention embodies a cup-shaped insulating base 1 having a metallic cover 2 sealably secured thereto as by studs or in any other desired manner and with an insulating sheet 3 disposed back of the cover 2.

A generally S-shaped conducting connector 4 is disposed at the forward end of the base 1 and extends through an opening 5 in the bottom 6 of the base to the exterior and is rigidly held in position within the base by a stud 7. At its exteriorly disposed end, the connector 4 carries a terminal stud 8 for securing a cable lead to the breaker while a stationary contact surface 9 is mounted upon the interior end thereof. A second conducting connector 11 is provided at the rear of the base 1 and comprises two elements 12 and 13 rigidly fastened together by a rivet 14 with the element 12 being secured to the rear wall 15 of the base by a stud 16 and with the element 13 secured to the bottom of the base by a stud 17 to thereby rigidly maintain the connector in place. Element 12 extends through an opening 18 in the bottom 6 to the exterior and carries a terminal stud 19 at its outer end. A bimetallic element 21 is rigidly welded or otherwise secured to the interiorly disposed end of the connector element 12. A member 22 is disposed within a recess 23 in base 1 and maintained therein by the defining walls of the recess and by a stud 24 threaded through the member. The stud 24 is adapted to bear against the connector 12

and serves as an adjusting or calibrating means for the bimetallic element.

A metallic frame or support 25 is provided within the base 1 spaced from the bottom 6 of the base and held in position therein by ribbed formations, not shown, on the side walls. A pin 26 is carried by the support 25 and provides a pivot upon which is pivotally mounted a manual operator 27 comprising a body portion formed of molded insulation and having a handle portion 28 extending through an opening in the cover 2 to the exterior of the switch, also an actuating member 29 and a contact lever or switch member 31, the latter having portions thereof disposed on opposite sides of the manual operator 27 and the pivotal or actuating member 29. A contact surface 32 is provided at the forward end of the switch member 31 and is adapted to cooperate with stationary contact 9 to complete a circuit therethrough. The pivot 26 is located intermediate the ends of the switch member 31 and since the manual operator 27 and the member 29 are mounted on this pivot they are thus disposed intermediate the ends of the switch member. The operator 27 is provided at its underside with a depending portion 33 carrying a pivot 34 on which is mounted a spring guide 35. The switch member 31 carries a cross piece 36 having a slot 37 extending therethrough adapted to receive the free end of the guide member 35. A compression spring 38 is disposed about the guide 35 and is interposed between shoulder formations on the guide and the cross piece 36 for a purpose to be described. A spring 39 having one end secured to the lower part of the pivotal member 29 and its opposite end fixed to a projection 41 on the support 25 continually biases the pivotal member 29 for counterclockwise movement. The operator 27 is cut away as at 42 and is thereby adapted to be manually moved in the normal operation of the switch without affecting the pivotal member 29. The depending portion 33 of the operator 27 is disposed immediately adjacent the pivotal member 29 when the contacts are engaged and is adapted both to move the pivotal member 29 or to be moved thereby under certain conditions to be hereinafter described. In the normal position of the pivotal member 29, the lower tip 43 thereof engages the free extremity 50 of the bimetallic element 21 and is retained in this position against the bias of spring 39. A flexible lead 44 interconnects the bimetallic element 21 and the switch member 31, being connected to that part of switch member 31 not shown in the cross-section views of Figures 2

and 3, to place the bimetallic element in series circuit with the contact. A generally L shape insulating fibre member 45 is secured to the connector 11 by the rivet 14 and is disposed between the flexible lead 44 and the bimetallic element 21 to prevent short circuiting therebetween; for a clearer presentation of the device that portion of the fibre member 45 which is disposed to the left of cutting line II-II of Figure 1 is shown in dotted outline in Figures 2 and 3. A flange 40 on the support 25 provides a stop adapted to engage a portion of the switch member 31 to define the extent of pivotal movement thereof in a clockwise direction.

Disposed against an interior plane surface of the connector 4 and secured in place by stud 7 is a bracket member 46 carrying a pin 47 upon a leg 48 thereof. Rotatably mounted upon the pin 47 is a generally L-shaped actuating member 49 comprised of molded Bakelite and carrying a detent pin 51. A spring 52 is coiled about the pin 47 and has one extremity engaging the bracket member 46 and the other extremity bent to engage the L-shaped member 48 to continually bias it and the detent pin 51 thereon for movement in a clockwise direction.

The breaker is provided with a circular opening extending through the cover 2, the insulating sheet 3 and into a partial substantially circular recess 53 provided in the base 1 and with the recess communicating with the interior of the base. An indicating pin 54 is disposed within the opening 53 and is movably retained therein by the detent pin 51, the free extremity of which extends into a recess 55 provided in the indicating pin 54. The indicating pin 54 will normally be maintained within the base 1 through its interconnection with the rotatable member 49, as is illustrated in Figure 2, being movable therefrom upon actuation of the rotatable member 49 in a clockwise direction. This movement of the rotatable member moves the detent pin 51, which moving effects rectilinear movement of the indicating pin 54 to carry a substantial part thereof beyond the cover 2. Ledge 56 provided by the bracket 46 is engageable by the detent pin 51 to thereby define the amount of clockwise movement of this pin and thus determine the extent of movement of the indicating pin 54 beyond the cover 2. The rotatable member 49 normally occupies the position illustrated in Figure 2, being carried to and maintained in this position against the bias of the spring 52 by the member 29 and being movable therefrom only upon the occurrence of an overload as will be hereinafter described.

The operation of the switch will now be described.

From the "on" position of Figure 2, the initial movement of the operating handle 27 counterclockwise to "off" position effects a compression of spring 38 to direct a force upon the switch arm 31 below its effective center of rotation, maintaining the contact engaged until the line of force of the spring 38 is carried through the pivot 26 whereupon the energy in the compression spring 38 becomes active to move the switch member 31 with a snap action in clockwise direction to disengage the contacts, the switch member 31 moving until it engages the limiting stop 40. To effect re-engagement of contacts, the manual operator 27 is moved in the reverse direction and a reverse action of the parts occurs.

In the automatic operation of the parts, the occurrence of an overload current heats the

bimetallic element 21 to bend it counterclockwise to move it out of engagement with tip 43 of the pivotal member 29, whereupon the pivotal member 29 moves counterclockwise under the bias of spring 39. The pivotal member in this movement engages depending portion 33 of the manual operator 27 for positive movement thereof to carry the line of force of spring 38 through the pivot 26 to move the switch member 31 to contact disengaged position with a snap action. Release of the actuating member 28 by the bimetallic element causes it to move out of engagement with the rotatable member 49 whereupon this member is free to rotate upon its axis under the bias of spring 52 to move the detent pin 51 which moves the indicating pin 54 to carry a substantial portion thereof beyond the cover 2 to thereby indicate the fact that an overload has occurred in the breaker. The indicating pin 54 may be vividly colored to more readily direct an observer's attention to the existence of an abnormality within the breaker.

To reset the breaker, the manual operator 27 is moved clockwise. The depending portion 33 in its resetting movement engaging and moving pivotal member 29 to a point slightly beyond the free end of the bimetallic element 21 where its tip 43 will be in position to re-engage the free end of the bimetallic element 21 upon release of the manual operator. This movement of the pivotal member 29 by the portion 33 will effect re-engagement of the member 29 with the rotatable member 49 to rotate it counterclockwise toward its normal position as illustrated in Figure 2. Movement of rotatable member 49 moves detent pin 51 thereon counterclockwise to carry the indicating pin 54 back into the breaker. This resetting movement of the manual operator also effects a snap movement of the switch member 31 into contacts engaged position, for the line of force of spring 38 will be carried through the pivot 26, the snap movement of the switch member occurring substantially simultaneously with the movement of the pivotal member 29 beyond the free end of the bimetal 21. With release of the manual operator 27 the tip 43 moves toward re-engagement with bimetal 21 under the bias of spring 39 and if the condition of overload still exists, the parts will promptly disengage for the heat created by the flow of overload current will move the free end of the bimetallic member 21 out of latching position and the parts will move again to "off" position and the detent pin 51 will rotate clockwise to again move the indicating pin 54 to carry the upper portion thereof beyond the cover 2 thereby signifying that an overload condition still exists.

It is seen, however, that the construction herein described permits the contacts to be held engaged, even though a condition of overload exists, by holding the manual operator in the "on" position, to provide for a situation where the operator finds it necessary to maintain a circuit despite the existence of an overload current. It is to be noted that if the manual operator is held in the "on" position, the pivotal member 29 will continue to restrain the rotatable member 49; thus the indicating member 54 cannot move out of the breaker to disclose the presence of an overload current. The fact that the indicating member 54 is hidden informs the operator that a circuit is being maintained.

While certain preferred embodiments of the invention have been specifically disclosed, it is understood that the invention is not limited

thereto as many variations will be readily apparent to those skilled in the art and the invention is to be given its broadest possible interpretation within the terms of the following claims:

What is claimed is:

1. In a non-trip free manually and automatically operated electric circuit breaker, stationary and movable contacts, switching means for effecting movement of said movable contact into and out of circuit making position, a manual operator movable to move said switching means, means responsive to an overload current for actuating said switching means to circuit breaking position, overload condition indicating means movable from an inactive position to an indicating position on the occurrence of an overload current, said indicating means comprising a movable member mounted separately from said manual operator and normally adapted to move independently thereof on the occurrence of an overload current, and means under the control of said manual operator for maintaining said indicating means in said first position even on the occurrence of an overload current when said manual operator is restrained in contacts "on" position.

2. In an automatic electric circuit breaker, a stationary contact, a movable contact, a switching arm for effecting movement of said movable contact into and out of engagement with said stationary contact, a manual operator, means for effecting snap movement of said switching arm in response to movement of said manual operator, a bimetallic element, a spring biased actuating member for moving said switching arm, said actuating member being independent of said snap means and being normally held by said bimetallic element in an inoperative position, and being releasable by said bimetallic element on the occurrence of an overload current to positively move said manual operator to "off" position to effect snap movement of said switching arm to contacts disengaged position, an overload indicating means adapted to be maintained in inoperative position during manual operation of the switching arm to contacts "on" and "off" position, and means operable on the occurrence of an overload current to move said indicating means to a position indicating the overload condition.

3. In an automatic electric circuit breaker, separable contacts, a switching arm for effecting separation of said contacts, a manual operator, means for effecting snap movement of said switching arm in response to movement of said manual operator, a bimetallic element, a spring biased pivotal actuating member for moving said switching arm, said actuating member being normally held by said bimetallic element in inoperative position, and being releasable by said bimetallic element on the occurrence of a predetermined overload current to move to effect snap movement of said switching arm to contacts separated position, an overload indicating means, a pivotal member operatively associated with said indicating means and mounted independently of and separate from said actuating member and engaged by said actuating member to maintain said indicating means in a non-indicating position during manual operation of said switching arm, said pivotal member being released for movement when said actuating member moves on the occurrence of a predetermined current overload, to move said indicating means to a position indicating current actuation of the breaker as distinguished from manual actuation, said manual operator being actuatable after automatic

operation of the breaker to reset simultaneously both said pivotal actuating member and said indicating means.

4. In an automatic electric circuit breaker, a stationary contact, a switching arm, a contact carried by said switching arm for cooperation with said stationary contact to make and break an electric circuit therethrough, a manual operator, means for effecting snap movement of said switching arm in response to movement of said manual operator, a bimetallic element, a spring biased actuating member for moving said switching arm, said actuating member being normally held by said bimetallic element in an inoperative position and being releasable by said bimetallic element on the occurrence of a predetermined overload current to positively move said manual operator to "off" position to effect snap movement of said switching arm to break the electric circuit through the breaker, an overload indicating member, said indicating member being maintained in non-indicating position during manual operation of said switching arm but being adapted to move to a position indicating automatic operation of the device when a predetermined current overload occurs in the circuit, resetting means including said manual operator, said manual operator being actuatable to "on" position after automatic operation of the breaker to simultaneously return both said actuating member and said indicating means to their initial position.

5. In an automatic electric circuit breaker, stationary and movable contacts, a switching arm movable to move said movable contact, for engagement and disengagement with said stationary contact, a manual operator, snap acting means associated with said switching arm and actuatable by said manual operator to effect snap movement of said switching arm, an actuating member, spring means biasing said actuating member for movement, a bimetallic element, said bimetallic element engaging said actuating member to hold it against the bias of said spring means, said actuating member being released by said bimetallic element on the occurrence of a current overload to effect actuation of said snap acting means, an overload indicating means, a movable member normally engageable by said actuating member and operatively associated with said indicating means and mounted independently of said actuating member and of said switching arm and adapted to maintain said indicating means in a non-indicating position during manual operation of the switching arm, said movable member moving on the occurrence of a current overload to effect movement of said indicating means to a position indicating automatic, as distinguished from manual, operation of the breaker, said manual operator after automatic operation of the breaker being actuatable to return said actuating member into its normally engaged position, said actuating member when moving to its engaged position being adapted to move said movable member to return said indicating means to its initial position.

6. In an automatic electric circuit breaker, a stationary contact, a movable contact, a switching arm movable to move said movable contact to separated and engaged position to effect the switching operation, a manual operator, snap-acting means associated with said switching arm and actuatable by said manual operator to effect snap movement of said switching arm, a pivotal actuating member, spring means for biasing said actuating member toward said manual opera-

tor, a bimetallic element, said bimetallic element releasably engaging said actuating member to hold it against the bias of said spring means, said actuating member being released by said bimetallic element on the occurrence of a predetermined overload current to move into engagement with said manual operator for positive movement thereof to "off" position to actuate said snap-acting means to effect snap movement of said switching arm, an overload release indicating member, a spring biased pivotal member operatively associated with said indicating means and mounted independently of said actuating member and engageable by said actuating member, said pivotal member normally acting upon said indicating member to maintain it in a non-indicating position during man-

ual operation of the switching arm, said pivotal member being released by said actuating member on the occurrence of a current overload for movement under its spring bias to effect movement of said indicating means to a position indicating current actuated operation of the breaker as distinguished from manual operation thereof, said manual operator after automatic operation of the breaker being operable toward "on" position to engage with and positively move said actuating member into a position where it is reengaged by said bimetallic member, said actuating member in this movement being engageable with said pivotal member for positive movement thereof to return said indicating means to its initial position.

JOSEF J. ZELLER.
